UNITED STATES PATENT OFFICE.

LOUIS A. SWEM, OF BELLINGHAM, WASHINGTON.

SPARK-ARRESTER.

1,100,034.

Specification of Letters Patent. Patented June 16, 1914.

Application filed April 30, 1912. Serial No. 694,261.

To all whom it may concern:

Be it known that I, LOUIS A. SWEM, a citizen of the United States of America, and a resident of the city of Bellingham, in 5 the county of Whatcom and State of Washington, have invented certain new and useful Improvements in Spark-Arresters, of which the following is a specification.

My invention has for a primary object to 10 provide a construction of the above type which will serve in an efficient manner in arresting or preventing the escape of sparks or live cinders from the stack or other conduit without undue interference with the 15 draft or exhaust operations of the locomotive or other engine in conjunction with which the device may be employed.

A further object resides in the provision 20 of mechanism for regulating the draft.

Other objects will be set forth as my description progresses and those features of construction, arrangements and combinations of parts on which I desire protection, succinctly defined in my annexed claims.

Referring to the accompanying drawings 25 wherein like numerals of reference indicate like parts throughout: Figure 1 is a vertical section of a spark arrester embodying the invention. Fig. 2 is a horizontal section taken 30 on line 2—2 of Fig. 1, and Fig. 3 is a modification thereof.

Referring to the drawing by numerals of reference, 1 indicates a casing having a top wall 2 provided with a centrally disposed 35 outlet opening 2'. Surrounding opening 2' is a cylindrical wall or flange 3 depending from wall 2 and spaced inwardly in concentric relation to the upper cylindrical portion 1' of the casing side wall to provide 40 what I term a "steam chamber" 4 into which the unconsumed products of combustion and exhaust steam escaping from the stack or spark conduit, as 5, are directed in a manner hereinafter to be described.

The cylindrical side wall portion 1' extends 45 below wall or flange 3 and connects with a substantially frusto-conical wall section 1'' whose reduced lower end portion is of greater diameter than stack 5 and provided with a cylindrical terminal portion 1^a which extends about and forms in conjunction 50 with the stack an outlet 6 serving to relieve stack 5 from back pressure resulting from the products striking the wall 2 within 55 chamber 4. This is an important feature of

my invention, as in practice I have found that through the provision of said outlet 6 I can employ chamber 4 without impairing or retarding the draft or natural flow or delivery of the products from the stack. 60

Outlet 6 must obviously not be so large as to interfere with the circulation through outlet 2', and to obtain a nicety of balance in size between the outlets 2' and 6 that the desired condition can be maintained under 65 varying atmospheric or other conditions, I provide what I term a "deflector" for outlet 6.

In the construction shown in Fig. 3, the deflector, as 7', comprises an annular plate 70 carried by a sleeve 8', slidably mounted on stack 5 for adjustment toward and from outlet 6 and provided with a set-screw 9, whereby the deflector can be securely held in its adjusted position. 75

In the construction shown in Figs. 1 and 2 I have shown a deflector 7 as constituting the bottom wall of a chamber 10 which latter extends upwardly about casing 1 in spaced relation thereto to provide an uptake passage for delivery of the quenched products in an upward direction, as may be desired when the device is applied to the stack of a locomotive. 80

Deflector 7 is fixed to a sleeve 8 slidably 85 engaged with stack 5 and adjustably held in position by threaded stems 11 which engage in apertured lugs 12 of casing 1 and are provided with nuts 13, as shown.

Reference numeral 14 indicates a conical 90 deflector having upper and lower stem extensions 15 and 16, the latter of which is guided for vertical movement in a spider 17 in stack 5 and the former having its upper end portion guided in a spider 21 in wall 3 95 and adjustably connected by nuts 18, as shown, with a lever 19, fulcrumed at 20 on casing 1.

The upper portion of deflector or valve 14 is of greater diameter than wall 3, which in 100 turn is of greater diameter than stack 5, and through the provision of lever 19, said deflector 14 can be adjusted upwardly to close outlet 2', as when a decreased draft is desired. 105

Lever 19 can be operated in any desired manner. For the purpose of illustration, I have shown the same provided with a cord 22 which can lead to any desired point for convenient operation. 110

Reference numeral 23 indicates spacer arms by which casing 1 is supported on stack 5.

In operation, deflector 14 serves to direct 5 the products of combustion and exhaust steam discharged from stack 5 upwardly into chamber 4. The steam collects in this chamber and quenches the sparks and live cinders, and the heavier products through their im- 10 pact with wall 2 are forcibly thrown downwardly through outlet 6. Between the exhaust operations the lighter products will pass through outlet 2'.

Having thus described my invention what 15 I claim as new, and desire to secure by Letters Patent of the United States of America, is:—

1. A spark arrester comprising a casing adapted to be mounted on a stack, said casing being open at its lower end to normally provide an outlet opening at the outer side of the stack and provided in its upper portion with an outlet opening, outwardly projecting lugs on said casing, valve means for 25 the outlet opening in the upper portion of the casing, a vertically adjustable deflector normally extending across the outlet opening in the lower end of said casing in outwardly spaced relation thereto, and a vertically disposed wall on said deflector extending upwardly about said casing and spaced therefrom, said wall being adjustably secured to said lugs.

2. A spark arrester comprising a casing 35 of inverted frusto-conical formation, a spark conduit normally projecting into the lower end of said casing, said casing having its lower end open about said spark conduit to provide an outlet opening and provided in 40 its top wall with an outlet opening, a wall depending from the top wall of said casing about the opening thereof and spaced inwardly from the side wall of said casing, valve means for the outlet opening in the top wall of said casing, a vertically 45 adjustable deflector extending across the outlet opening in the lower portion of said casing in outwardly spaced relation thereto, and a vertically disposed wall on 50 said deflector extending upwardly about said casing and spaced therefrom.

3. A spark arrester comprising a casing of inverted frusto-conical formation, a spark conduit normally projecting into the lower 55 end of said casing, said casing having its lower end open about said spark conduit to

provide an outlet opening and provided in its top wall with an outlet opening, a wall depending from the top wall of said casing about the opening thereof and spaced inwardly from the side wall of said casing, valve means for the outlet opening in the top wall of said casing, and a deflector mounted on said spark conduit for vertical adjustment and extending across the outlet 60 opening in the lower portion of said casing in outwardly spaced relation thereto.

4. A spark arrester comprising a casing of inverted frusto-conical formation, a spark conduit normally projecting into the lower 65 end of said casing, said casing having its lower end open about said spark conduit to provide an outlet opening and provided in its top wall with an outlet opening, a wall depending from the top wall of said casing about the opening thereof and spaced inwardly from the side wall of said casing, upwardly flaring means in said casing interposed between said spark conduit and said 70 depending wall for directing the smoke 75 from the former into the upper portion of the casing at the outer side of said depending wall, and a deflector extending about said spark conduit across and in outwardly spaced relation to the outlet opening in the 80 lower portion of said casing and adjustable toward and from the same.

5. A spark arrester comprising a casing of inverted frusto-conical formation, a spark conduit normally projecting into the 85 lower end of said casing, said casing having its lower end open about said spark conduit to provide an outlet opening and provided in its top wall with an outlet opening, a wall depending from the top wall of 90 said casing about the opening thereof and spaced inwardly from the side wall of said casing, valve means for the outlet opening in the top wall of said casing, a vertically 95 adjustable deflector normally extending across the open lower end of said casing in outwardly spaced relation thereto, and a vertically disposed wall on 100 said deflector of inverted frusto-conical formation extending upwardly about the similarly formed 105 portion of said casing and spaced therefrom.

Signed at Bellingham, Wash., this 11th day of April, 1912.

LOUIS A. SWEM.
